UNITED STATES PATENT OFFICE.

GUSTAV J. SENGBUSCH, OF MILWAUKEE, WISCONSIN.

INK PAD.

Application filed August 11, 1924. Serial No. 731,259.

To all whom it may concern:

Be it known that I, GUSTAV J. SENGBUSCH, a citizen of the United States, and a resident of Milwaukee, county of Milwaukee, 5 and State of Wisconsin, have invented certain new and useful Improvements in Ink Pads, of which the following is a specification.

My invention relates to inking devices, 10 rubber stamps and the like, wherein an inked pad is mounted in a holder or case which exposes the upper surface of the pad.

The principal objects of my invention are to provide an improved inking pad and 15 holder or case therefor; to construct the pad so that it may be re-inked in a more convenient and satisfactory manner than heretofore; to permit reversal of the pad; to afford a new inking surface which may be 20 exposed for use while the other side of the pad is absorbing a new supply of ink; and to provide an improved pad holder which may be conveniently taken apart for the purpose of removing and reversing the pad.

25 On the drawings:

Fig. 1 is a perspective view of my new ink pad structure, with the cover of the case closed;

Fig. 2 a top view thereof, with the cover 30 open and portions broken away to disclose details of the construction;

Fig. 3 a sectional view, taken on the line 3—3 of Fig. 1;

Fig. 4 a top view of the base of the ink 35 pad holder;

Fig. 5 a top view of the ink pad proper or inking element with portions broken away to disclose details of the construction; and

Fig. 6 a view of the separate parts 40 composing the inking pad, preparatory to assembling.

Referring to the drawings, the reference numeral 1 indicates the inking pad proper as a whole which is composed of two layers

45 2 of felt or other suitable absorbent material, with a perforated plate 3 interposed therebetween. A fabric covering 4 is arranged at the outer side of each layer 2 of felt, and the entire pad structure is combined 50 in the assembled form by stitching around the edges as indicated at 5, or in any other convenient manner.

The holder for this pad comprises a base 6 which is preferably of wood and formed 55 with an elevated portion or deck 7 of reduced size, with an annular flange or bead

8 around the lower edge, and this elevated portion 7, which is of substantially the same size as the pad 1, may be tapered somewhat as shown in Fig. 3. The inked pad 1 is 60 supported on the upper surface of the reduced portion or deck 7 of the base, and the latter is preferably provided with a covering 9 of tinfoil or other material on the upper surface to prevent the ink from the 65 pad being absorbed by the wooden base.

For holding the pad 1 on the base 6, there is a shell 10 formed with a marginal depending flange which fits somewhat snugly around the elevated portion 7 of the base 70 and having an inturned flange 11 around the upper edge which projects over the edge of the pad 1 and holds the latter down on the upper surface of the portion 7 of the base. A round headed tack 12 or other suitable means is driven into each end of the elevated portion 7 of the base, and the depending flange at each end of the shell 10 is provided with a correspondingly arranged indentation 13 on the inner face to engage 80 the rounded heads of the tacks 12 and hold the shell 10 in place on the base.

A cover 14 is hinged to the shell 10 to close the large opening through the top of the shell to which the upper surface of the 85 pad 1 is exposed, said cover being provided with depending ears 5 secured by pivot pins 16 to the shell.

With the pad 1 and the casing constructed as above described, it will be observed that 90 the pad is reversible and that the shell may be readily removed to permit the reversal of the pad. When the one surface of the pad requires re-inking, the ink is applied to said surface and the pad preferably reversed in the case. This brings the other surface of the pad to the top and allows the 95 ink which has just been applied to penetrate the pad before the re-inked surface is again used.

While I have shown and described my invention in a preferred form, I am aware that various changes and modifications may be made without departing from the principles of my invention, the scope of which is to be 100 determined by the appended claims.

I claim as my invention:

1. In an inking device for rubber stamps and the like, the combination of a reversible pad, a base for supporting the pad, and a removable shell on said base for holding the pad thereon, said shell having an inturned 110

flange for engaging the marginal edge of the pad and a depending flange frictionally engaging the base to hold the shell thereon.

5. In an inking device for rubber stamps and the like, the combination of a base having an elevated supporting surface, a shield on said surface, a reversible pad mounted on said shield, and a removable shell frictionally engaging the base for holding the 10 pad thereon.

3. In an inking device for rubber stamps and the like, the combination of a base having an elevated portion, an ink pad on the 15 upper surface of said elevated portion, a shell for holding the pad on the elevated portion of the base, and interengaging means on the shell and base adapted to yieldingly interlock for detachably holding the pad on the base.

20. 4. In an inking device for rubber stamps and the like, the combination of a base having an elevated portion, an ink pad on the upper surface of said elevated portion, a shell having a depending flange embracing 25 the elevated portion of the base and having an inturned flange for holding the pad on

the elevated portion of the base, recesses on the inner face of the depending flange and headed members on the edges of the elevated portion of the base with which said recesses 30 detachably interlock to hold the shell on the base.

5. In an inking device for rubber stamps and the like, the combination of a base having an elevated portion, an ink pad on the 35 upper surface of said elevated portion, a shell for holding the pad on the elevated portion of the base, interengaging means on the shell and base adapted to yieldingly interlock for detachably holding the pad on 40 the base, and a cover hinged to the ends of the base and adapted to be arranged over the pad in contact with the shell.

6. In an ink pad, the combination of two layers of absorbent material, a fabric sheath 45 entirely enclosing same on both sides over each layer, and a stiffening member interposed between and enclosed by the two layers of absorbent material and having a plurality of openings therethrough.

GUSTAV J. SENGBUSCH.
